UNITED STATES PATENT OFFICE.

JOSEPH T. ROBIN, OF NEW YORK, N. Y., ASSIGNOR TO ALBERT KUNSTADTER, MAX KUNSTADTER, AND SAM KUNSTADTER, COMPOSING THE FIRM OF KUNSTADTER BROTHERS, OF CHICAGO, ILLINOIS.

DESIGN FOR A SHOW-CASE.

SPECIFICATION forming part of Design No. 36,992, dated June 21, 1904.

Application filed April 25, 1904. Serial No. 204,911. Term of patent 7 years.

To all whom it may concern:

Be it known that I, JOSEPH T. ROBIN, a citizen of the United States, residing at New York, in the county of New York and State of New York, have invented a new, original, and ornamental Design for a Show-Case, of which the following is a specification, reference being had to the accompanying drawing, which shows a perspective view of a show-case embodying my new design.

What I regard as new, and desire to secure by Letters Patent, is—

The ornamental design for a show-case, as herein shown.

JOSEPH T. ROBIN.
